INVENTOR:

Chas. Beck,
BY John A. Diederichs, ATTORNEY.

UNITED STATES PATENT OFFICE.

CHARLES BECK, OF PHILADELPHIA, PENNSYLVANIA.

PICTURE AND CARD SUPPORTER.

SPECIFICATION forming part of Letters Patent No. 257,542, dated May 9, 1882.

Application filed March 16, 1882. (No model.)

To all whom it may concern:

Be it known that I, CHARLES BECK, a citizen of the United States, residing in the city and county of Philadelphia, State of Pennsylvania, have invented a new and useful Improvement in Picture and Card Supporters, which improvement is fully set forth in the following specification and accompanying drawings, in which—

10 Figure 1 is a view of the outer face of the supporter embodying my invention. Fig. 2 is a side elevation of a picture or card having my invention applied to it. Fig. 3 is a rear view thereof, the supporter being folded. Fig. 4 is 15 a vertical section in line $x x$, Fig. 3.

Similar letters of reference indicate corresponding parts in the several figures.

My invention consists of a supporter for a picture, calendar, or other card or plate, formed 20 of a piece of suitable material, combining a leg, a base, and means for attachment to the card or plate, the parts being continuous of each other, so that the base extends from the bottom of the leg to the card or plate and forms 25 a large and flat surface for supporting said card or plate.

It also consists in forming the supporter with a tongue which is adapted to interlock or engage with a tongue on the card or plate, whereby 30 the supporter and card or plate are prevented from separation.

It also consists in making the supporter adjustable, whereby it is adapted for cards or plates of different sizes.

35 Referring to the drawings, A represents the supporter, which is formed of a piece of suitable stiff material, preferably pasteboard or card-board, and having on its outer face transversely-extending scores or folding-lines $a b c$, 40 thus producing the parts $d e f g$, which are continuous of each other, the part d forming a flap, one side of which is gummed, so that said part may be secured to a picture, calendar, or other card or plate, B. (Shown by dotted lines.)

45 The part e constitutes the leg of the support, and the part f the base thereof. The part g constitutes a tongue, which is adapted to engage with a tongue, C, secured by gumming or otherwise to the card or plate B. It being 50 noticed that the parts $e f$ are continuous, the part d is at the end of the part e , and the part g is at the end of the part f , and the four parts

are formed of one piece of material; but they may be separate pieces gummed to each other in the order named. The tongue C is cut from the part e or f —preferably the part f —thus utilizing either part for the formation of the tongue and rendering the supporter light and graceful; but said tongue may be formed from a separate piece of material. When the flap 60 d is secured to the back of the card or plate the parts are spread at or about an acute angle, the part e thus forming an upright or leg and the part f forming a large and flat base, which is rested on the table or other place of 65 location of the card or plate. The lower portion of the tongue C is separated from the card or plate, leaving a space or pocket, in which is inserted the part or tongue g , thus locking the tongues. It will be seen that the card or plate 70 is nicely sustained by the leg and base $e f$, and the separation of the base from the card or plate is prevented by the engagement of the tongues $g C$. Consequently the card or plate retains its proper position for viewing or inspection without liability to shift or slip from the base. By disengaging the tongues the parts $f g$ may be folded on the inner face of the 75 part e , and then on the back of the card or plate. As the part f has a piece cut from it 80 corresponding to the shape of the tongue C, the latter occupies the space of said part as cut out, and thus the supporter is nicely and compactly folded on the card or plate, it being evident that the part e may also be cut out the 85 shape of the tongue C in reverse order, as shown in Fig. 1. On the outer face of the supporter are additional score-lines $a' c'$, whereby the lengths of the leg e , base f , and tongue g may be adjusted; and the rear face of the 90 tongue C is provided with a score-line, c'' , for purpose of adjusting its length, the parts being folded at said score-lines without, however, being changed in the operation.

Having thus described my invention, what 95 I claim as new, and desire to secure by Letters Patent, is—

1. The picture or card supporter consisting of the attaching part d , the leg e , and base f , formed of a continuous piece of material in the 100 order named, whereby the base extends from the bottom of the leg to the picture or card, substantially as and for the purpose set forth.

2. The supporter formed of the attaching

part *d*, leg *e*, and base *f*, having a tongue, *g*, in combination with the tongue *C* of the card or plate, substantially as and for the purpose set forth.

5 3. The supporter *A*, formed with the additional score folding-lines *a' c'*, substantially as and for the purpose set forth.

4. The tongue *C*, adapted to be secured to

the card or plate and formed with the score-line *c''*, substantially as and for the purpose set forth.

CHAS. BECK.
